RAILWAY CAR

William E. Wine, Toledo, Ohio

Application March 18, 1929. Serial No. 348,081

34 Claims. (Cl. 105—280)

My invention relates to railway cars and more particularly to closures or doors employed in flat-bottom gondola cars and the like.

A principal object of the invention is to provide a closure for the lading discharge opening of a railway car which is of rugged construction and may be easily operated by a trainman.

A principal feature of the invention consists in integrally forming the closure with a plurality of substantially parallel reinforcing members or flanges.

Another feature of the invention resides in constructing the closure with a plurality of substantially parallel reinforcing members and with 15 a member connecting said reinforcing members intermediate their ends.

A further feature of the invention consists in integrally forming the door with a plurality of connected reinforcing members, one of said members affording means to which an arm may be attached for cooperating with mechanism carried by the car to support the closure in operative position.

A still further feature of the invention consists 25 in integrally forming the door arm with a lug or projection adapted to cooperate with a removable door operating lever.

A still further feature of the invention resides 30 in constructing the closure in sections and in providing means interlocking said sections so as to prevent them from moving away from each other along their hinge axes.

Other and more specific features of the invention residing in advantageous forms and combinations of parts will hereinafter appear and be 35 pointed out in the claims.

In the drawings illustrating a preferred embodiment of the invention:

Figure 1 is a fragmentary plan view of a flat- 40 bottom gondola railway car.

Figure 2 is a side elevational view of that portion of the car construction illustrated in Figure 1.

Figure 3 is a sectional view taken on line 3—3, 45 Figure 1.

Figure 4 is a plan view, partly in section, illustrating portions of the closure.

Figure 5 is a view, partly in section and partly in elevation, taken on line 5—5, Figure 4.

Figure 6 is a sectional view taken on line 6—6, 50 Figure 1.

Figure 7 is a fragmentary plan view illustrating the manner in which the sections comprising the closure are interlocked.

Figure 8 is a sectional view taken on line 8—8, 55 Figure 7.

Figure 9 is an elevational view of the construction illustrated in Figure 7.

Figure 10 is a perspective view of the door arm.

Figure 11 is a view corresponding to Figure 7 illustrating a modified construction for interlocking the closure sections.

Figure 12 is an elevational view of the construction illustrated in Figure 11.

As the type of car chosen for illustrating the invention is of the well-known flat-bottom gondola type only portions of the car structure have been shown and it is to be understood that the structure illustrated is duplicated on the opposite side of the car.

Referring more particularly to the drawings 1 70 indicates one of the side members of the center sill and 2 the usual top cover-plate thereof. The car floor 3 which is spaced above the center sill is preferably of sheet metal and may be formed with any number of openings 4, only one of 75 which is illustrated, through which the lading of the car may be discharged. At the opposite sides of the car the floor is respectively secured by rivets 5 to the lower inwardly projecting flange 6 of the channel shaped side sills 7. The car sides 80 may be conveniently formed with metal plates or sheets 8 secured in overlapping relation to the outer face of the side sill in any suitable manner (not shown).

The lading discharge opening 4 may be closed 85 by a door or closure 9 hingedly connected to the car so as to swing to open position under the influence of gravity. In order to permit the type of car illustrated to be quickly emptied of its 90 contents it is the usual practice to make the discharge openings relatively large. Correspondingly large closures must therefore be employed which, due to their weight, require considerable effort on the part of trainmen to raise them to closed position. Especially is this true when east doors are employed. To overcome this difficulty each of the closures is preferably made in two 95 sections 10 and 11, respectively, the sections being of such size and weight that they may be easily operated and being so arranged and related that they in effect act as one door when in operative position.

Each of the sections is preferably made of 100 cast steel and is formed with downwardly projecting marginal flanges 12. The marginal flanges at the side edges of each section and that one at the hinged or inner edge thereof terminate in inwardly projecting flanges 13, while the marginal flange at the outer or free edge of the door terminates in an outwardly projecting 105 110

flange 13'. Thus the side and inner edges of the sections are in effect channel shaped and the outer edge thereof Z-shaped.

Rigidly secured to the center sill are a plurality of brackets 14 for hingedly connecting the closure to the car, each of the brackets being formed with a base-plate 15 and upwardly projecting side flanges 16. The base-plate of each bracket is suitably apertured to receive rivets 17 for connecting them to the center sill. The side flanges of each of the brackets are fashioned with inwardly projecting hub portions 18 which are spaced apart a suitable distance to receive lugs 19 with which the closure sections are formed. The hub portions 18, side flanges 16 and base-plate 15 of the brackets may conveniently be reinforced by an upwardly extending web 20. Each of the hinge lugs 19 comprises a hub portion 21 connected to the marginal flange at the inner edge of the closure by a web portion 22. The hub portions 18 of the brackets and 21 of the lugs are respectively apertured to receive pins 23 of any suitable construction for hingedly mounting the closure on the car body.

To prevent the escape of fine lading between the adjoining edges of the sections a portion of one of them overlaps the adjacent portion of the other. In the present embodiment of the invention the section 11 is shown as being provided with a flange 24 projecting beyond the inner side marginal flange thereof in the plane of the main body portion of the section. This flange 24 overlappingly engages the upper surface of the section 10 adjacent its inner side edge, the overlapped portion of the latter section being depressed or recessed as at 25 to receive the flange so that the upper surfaces of the two sections will be disposed in substantially the same plane when in closed or operative position. In order that the plane of the top surfaces of the sections may coincide with that of the top surface of the floor the portions of the former adjacent its marginal edges are depressed as at 26 to receive in overlapping relation neighboring portions of the floor and side sill. Thus it will be seen that since the adjoining edges of the door are in overlapping relation and that the portions of the floor and side sill defining the lading discharge opening overlie adjacent portions of the closure, the lading within the car is effectually prevented from accidentally escaping therefrom.

The outer face of each door section may be advantageously integrally formed with a plurality of parallel reinforcing members or flanges 27 which are disposed inwardly of the side marginal flanges and are preferably normal to the hinge axis thereof. These flanges 27 are disposed in planes intersecting the hinge lugs 19 and in order to rigidify the latter the flanges are formed with downwardly projecting extensions 28. Since the reinforcing flanges extend continuously from the inner or hinged edge of each section to the outer or free edge thereof they serve to effectually tie together the marginal flanges of the sections at those points. Adjacent their outer ends the flanges are connected or tied together by a reinforcing member 29 which is disposed inwardly of the free edge of the door. This member is of angular shape having a portion 30 substantially normal to the plane of the section and a flange 31 substantially parallel thereto, the bottom surface of the latter being disposed in the plane of the lower edge of the reinforcing flanges 27 which project downwardly from the door a distance equal to that of the marginal

flanges 12. Intermediate the reinforcing flanges 27 and substantially at the midpoint of the connecting member 29, each section is also preferably integrally formed with a flange 32. This flange extends only from the connecting member 29 to the marginal flange at the free edge of the door and, in addition to serving as means for connecting these portions of the sections, serves as means to which a door arm 33 may be secured.

The door arms 33 are offset intermediate their ends to pass beneath and outwardly beyond the marginal flange at the free edges of the sections and each is substantially channel shaped having a top flange 34, an intermediate or web portion 35 and a bottom flange 36. At its inner end the web 35 is apertured to receive rivets 37 for attaching it to the center reinforcing flange 32. The top flange 34 has portions 38 and 39 disposed in spaced planes and connected by an inclined portion 40, the portion 38 being apertured to receive rivets 41 for attaching it to the main portion of the door section and the portion 39 is apertured to receive a rivet 42 for attaching it to the outwardly projecting flange 13'. The portion of the flange 13' adjacent the door arm is preferably enlarged to afford sufficient metal for receiving the rivet without weakening the action of the flange 13' as a reinforcing flange. Projecting from the side of the web 35 opposite to that of the flanges 34 and 36 is an angular bracket having flanges 43 and 44, the flange 43 being disposed in the same plane as that of the outer portion 39 of the flange 34 and being apertured to receive a rivet 45 which serves as additional means for securing the outwardly projecting portion of the door arm to the section. The flange 44, in addition to a function to be hereinafter described, serves to strengthen the flange 43. The top flange 34 may likewise be strengthened by a portion or rib 46 which is in alignment with and 105 in effect constitutes a prolongation of the flange 44. At its outer end the bottom flange 36 of the door arm is tied to the upper flange 34 thereof by an end wall 47 while at its inner end it merges into the web 35.

Pivotedly mounted upon the side of the car are hooks 48 having a plurality of ledges 49 and 50, respectively, adapted to cooperate with the portion 39 of the top flange 34 of the door arm to support the sections in partially closed or fully 125 closed positions. Overlying the outer face of each of the hooks is a cover-plate 51 rigidly secured to the car by rivets 52 and 53 and 54 which pass through the cover-plate, side sheets 8 and side sill 7. The rivet 52 forms a pivotal support for the hook and the one designated 53 forms a pivotal support for a locking cam 55 which is interposed between the side sill and cover-plate for cooperating with the hook to prevent the latter from accidentally moving to unlocked position.

As considerable difficulty is often experienced in causing dump doors of railways cars to assume a fully closed position due to the distortion of the doors and their associated parts, the cover plate 51 may be formed with an outwardly projecting lug or flange 56 which is apertured as at 57 to receive a removable lever 58. In closing either one of the sections it may be raised to a position such that the ledge 49 of its associated hook will engage the flange 34 of the door arm to maintain and support the section in a preliminary or partial position of closure. The lever may then be inserted through the aperture 57 into engagement with the under surface of the flange 34 and

then caused to rotate on the cover plate as a fulcrum point to force the section into a position such that the ledge 50 of the hook may engage the flange 34 to support the door in a final or fully closed position. To obtain an increased leverage for easily and conveniently raising the door from an open to a partially closed position the flange 44 of the bracket on the door arm is fashioned with an aperture 59 for receiving a removable lever 60. This lever is also adapted to cooperate with the outer edge of the flange 43 of the bracket which is preferably formed with a bead or rib 61 to afford a suitable bearing for the lever. Should it not be convenient to employ the lever 60 in this manner a lever 62 may be used for the same purpose by cooperating with the flange 31 of the connecting member 29 and the lower edge of the marginal flange at the free edge of the door. While the levers 60 and 62 are primarily intended for use in moving the sections from open to partially closed position it will, of course, be appreciated that should it be unnecessary to make use of the mechanical advantage obtained by employing the lever 58 that these levers may also be used to move the door from partially to fully closed position. Thus it will be seen that the sections may be moved from open to fully closed position by the use of either of the levers 60 and 62 or by the combined use of either one of these levers and the lever 58. While the levers employed have been designated by different reference numerals it will, of course, be understood that the construction of each is the same and the form of lever employed and for which the parts have been designed to cooperate is the usual pry or crow bar employed in railway service.

In order to prevent the sections of the closure from moving away from each other in the direction of their hinge axes, means is preferably provided for interlocking them. The desired manner of interlocking the sections is illustrated in Figures 7 to 9 inclusive. In this form of the invention the outer corner of the section 10 adjacent the other section of the closure is formed with an aperture or recess 63 for receiving a downwardly projecting lug or boss 64 formed on the under surface of the side flange 24 of the section 11. To rigidify the outer end of the flange 24 the section 11 is fashioned with a laterally projecting flange 65 which, in effect, constitutes a prolongation of the outer marginal flange 12 of the section 11. The outer marginal flange of the section 10 is recessed as at 66 to receive the flange 65 so that the latter and the outer marginal flanges of both sections will be disposed in substantially the same plane. The adjoining edges of the flange 65 and the recessed portions 66 may be, if desired, inclined as clearly shown in Figure 9.

In the modified form of the invention illustrated in Figures 11 and 12 the front edge of the section 10 is formed with a rib or projection 67 adapted to extend into a recess 68 formed on the inner face of the of the flange 69 which projects laterally from the section 11. This flange 69 rigidifies the outer end of the flange 24 and overlies the outwardly projecting portion 13' of the outer marginal flange 13 of the section 10.

When it is desired to discharge the lading within the car, the sections of each closure may be caused to move to open position either separately or simultaneously. In causing them to move separately the hook supporting the section 10 will first be moved to an inoperative position

permitting that section to swing downwardly and then the hook supporting the section 11 may be moved to a similar position permitting that section to swing open. When it is desired to cause the sections to open simultaneously the supporting hook of section 11 is first moved to an inoperative position but due to the fact that the flange 24 thereof is in engagement with the top surface of the section 10, that section functions to support the section 11 in an elevated position. When, however, the hook supporting section 10 is moved to an inoperative position both of the sections will then simultaneously swing open. In the door closing operation it will, of course, be appreciated that it is always necessary to move the section 11 to closed position before the section 10 due to the disposition of the overlapping portions of the sections.

From the foregoing it will be evident that the closure, although made in two sections, functions when in closed position as a unitary door and that the sections are so constructed and reinforced that they will effectively withstand the severe surface conditions to which they are normally subjected.

I claim:

1. In a railway car having a lading discharge opening, a hingedly mounted closure for said opening integrally formed with a marginal flange adjacent its inner edge and with a plurality of hinge lugs disposed inwardly of said flange, the latter terminating in an inwardly projecting portion spaced from the main body of the closure, and a plurality of reinforcing members formed integrally with the closure and respectively extending from said hinge lugs to the opposite edge of the closure.

2. In a railway car having a lading discharge opening, a hingedly mounted closure for said opening integrally formed with a plurality of reinforcing members disposed inwardly of and substantially parallel with its side edges and being also integrally formed with a member connecting said reinforcing members, said connecting member being disposed inwardly of the free edge of the closure and being fashioned with a plurality of angularly disposed portions, one of which is substantially parallel to the plane of the closure.

3. In a railway car having a lading discharge opening, a hingedly mounted closure for said opening integrally formed with a plurality of spaced substantially parallel reinforcing members and with an angularly shaped member connecting said reinforcing members, said connecting member being disposed inwardly of the free edge of the closure and being adapted to cooperate with a removable closure operating lever.

4. In a railway car having a lading discharge opening, a hingedly mounted closure for said opening integrally formed with a plurality of substantially parallel reinforcing members and with a member connecting each of said reinforcing members, one of said reinforcing members being disposed substantially midway between the side edges of the closure, and an arm rigidly secured to said last-named member and projecting beyond adjacent portions of the car side for cooperating with mechanism to support the closure in operative position.

5. In a railway car having a lading discharge opening, a hingedly mounted closure for said opening having marginal flanges and integrally formed with a plurality of reinforcing members and with a member connecting said reinforcing

- members, said closure being also integrally formed with a member intermediate said reinforcing members and extending between said connecting member and the marginal flange at 5 the free edge of the closure, and means rigidly secured to said intermediate member and extending beyond the free edge of the closure for cooperating with mechanism carried by the car to support the closure in operative position.
- 10 6. In a railway car having a lading discharge opening, a hingedly mounted closure for said opening integrally formed with a plurality of reinforcing members and with a member connecting said reinforcing members, said connecting member extending on opposite sides of and disposed at the inner end of one of said reinforcing members, and an arm secured to said last-named reinforcing member and projecting beyond adjacent portions of the car side for cooperating 15 with mechanism carried by the car body to support the closure in operative position.
7. In a railway car having a lading discharge opening, a hingedly mounted closure for said opening integrally formed with a plurality of 20 reinforcing members and with a member adjacent the free edge of the closure connecting said reinforcing members, said closure being also integrally formed with a member extending between said connecting member and the free edge 25 of the closure adapted to receive an arm for cooperating with mechanism for supporting the closure in operative position.
8. In a railway car having a lading discharge opening, a hingedly mounted closure for said 30 opening having marginal flanges and integrally formed with a plurality of reinforcing members and with a member connecting said reinforcing members, said connecting member being disposed inwardly of and adjacent the marginal flange at 35 the free edge of the closure and being fashioned to support the inner end of a removable closure operating lever, said lever when in operative position being also engageable with the marginal flange at the free edge of the door.
- 45 9. In a railway car having a lading discharge opening, a hingedly mounted closure for said opening, an arm carried by the closure, and means carried by the car body for cooperating with the arm to support the closure in operative 50 position, said arm being integrally formed with a lug for cooperating with a removable closure operating lever.
- 55 10. In a railway car having a lading discharge opening, a hingedly mounted closure for said opening, an arm carried by the closure having oppositely projecting flanges, one of said flanges being cooperable with means carried by the car body for supporting the closure in operative position and the other of said flanges being cooperable with a removable closure operating lever.
- 65 11. In a railway car having a lading discharge opening, a hingedly mounted closure for said opening having at its free edge an outwardly projecting flange, and an arm carried by the closure and having oppositely projecting flanges secured to the said flange on the closure, one of said flanges being cooperable with means carried by the car for supporting the closure in operative position and the other of said flanges 70 having a downwardly extending portion cooperable with a removable closure operating lever.
- 75 12. In a railway car having a lading discharge opening, a closure for said opening, said closure involving a plurality of relatively movable sections, one of said sections having a projection overlying and adapted to be interlocked with a portion of the other of said sections and the upper surfaces of both of said sections being disposed in substantially the same plane.
13. In a railway car having a lading discharge opening, a hingedly mounted closure for said opening comprising a plurality of sections, and means interlocking said sections for preventing them from moving away from each other in the direction of their hinge axes. 80
14. In a railway car having a lading discharge opening, a hingedly mounted closure for said opening comprising a plurality of sections, one of said sections having a portion overlapping and interlocking with the other of said sections for preventing movement of the sections away from each other in the direction of their hinge axes. 85
15. In a railway car having a lading discharge opening, a hingedly mounted closure for said opening comprising a plurality of sections, one of said sections being provided with a recessed portion and the other being provided with a portion cooperable with the recessed portion for locking said sections together. 90
16. In a railway car having a lading discharge opening, a hingedly mounted closure for said opening comprising a plurality of relatively movable sections, one of said sections being provided with a recessed portion adjacent its free edge and the other of said sections having a portion overlapping the adjacent portion of said first-named section and provided with a downwardly extending projection cooperable with said recess for interlocking said sections. 100
17. In a railway car having a lading discharge opening, a closure for said opening involving two hingedly mounted relatively movable cast metal sections, each of said sections being integrally formed with a marginal flange at its free edge and with a flange substantially normal thereto, 110 an arm for each section rigid with the said normal flange and projecting outwardly beyond the said marginal flange, and a plurality of movable means secured to the car body and respectively cooperable with the outwardly projecting portions of said arms for supporting the sections in closed positions. 115
18. In a railway car having a lading discharge opening, a closure for the opening involving two hingedly mounted cast metal sections, each of 120 said sections being integrally formed with a marginal flange at its free edge and with a flange disposed substantially normal thereto and midway between its ends, an arm rigidly secured to the marginal and normal flanges of each section 125 and projecting beyond the free edge of the section, and a plurality of movable means secured to the car body and respectively cooperable with the projecting portions of said arms for supporting the sections in closed positions. 130
19. In a railway car having a lading discharge opening, a hingedly mounted cast metal closure for said opening integrally formed with a marginal flange adjacent its free edge, said marginal flange terminating in an angularly disposed outwardly projecting portion affording means to which a door arm may be secured. 135
20. In a railway car having a lading discharge opening, a hingedly mounted closure for said opening having marginal flanges, the marginal flanges at the side and hinged edges terminating in inwardly projecting portions and the marginal flange adjacent the free edge of the closure terminating in an outwardly projecting portion. 140
21. In a railway car having a lading discharge opening, a hingedly mounted closure for said opening comprising a plurality of sections, one of said sections having a projection 145

- opening, a hingedly mounted cast metal closure for said opening integrally formed with a marginal flange at its free edge, said flange terminating in an angularly disposed outwardly projecting portion substantially parallel with the main body portion of the door, and an arm secured to said angularly disposed portion and projecting beyond the free edge of the door for cooperating with means carried by the car body to support the door in closed position. 5 80
22. In a railway car having a lading discharge opening, a hingedly mounted closure for said opening integrally formed with a marginal flange adjacent its free edge, said flange terminating in an outwardly projecting portion substantially normal thereto, and an arm having a flange rigidly secured to said portion and projecting outwardly beyond the free edge of the door, and a member movably mounted on the car and cooperable with the outwardly projecting portion of said flange for supporting the closure in operative position. 15 85
23. In a railway car having a lading discharge opening, a hingedly mounted cast metal door for the opening integrally formed with a flange projecting beyond the free edge thereof and disposed in a plane spaced from and substantially parallel with the plane of the closure, an arm having a flange secured to the flange of the closure, and a hook pivotally mounted on the car body and engageable with the flange of the arm to support the closure in operative position. 20 90
24. In a railway car having a lading discharge opening, a cast metal closure for said opening having a plate-like body portion, the free edge of said closure being integrally formed with a marginal flange terminating in an outwardly projecting portion substantially parallel with said plate-like body portion, an arm provided with a flange rigidly secured to the plate-like portion of the closure and to the outwardly projecting portion of the marginal flange, said flange of the arm extending beyond adjacent portions of the car, and a movable member mounted upon the car body and engageable with the said flange of the arm for supporting the closure in operative position. 30 95
25. In a railway car having a lading discharge opening, a hingedly mounted closure for said opening, an arm carried by the closure, and means carried by the car body for cooperating with the arm to support the closure in operative position, said arm being provided with a plurality of angularly disposed portions respectively engageable with a removable lever adapted to serve as means for lifting the door toward closed position. 35 100
26. In a railway car having a lading discharge opening, a hingedly mounted closure for said opening, an arm carried by the closure, and means carried by the car body for cooperating with the arm to support the closure in operative position, said arm being provided with angularly disposed portions, one of said portions affording an abutment for a removable lever and the other having an aperture through which the lever is adapted to extend, said lever being adapted to serve as means for lifting the door toward closed position. 40 105
27. In a railway car having a lading discharge opening, a hingedly mounted closure for said opening, an arm carried by the closure having a portion substantially normal thereto, and a hook pivotally mounted upon the car body, said arm having a flange extending from one side of said normal portion for cooperating with the hook and means projecting from the other side of said portion for cooperating with a removable lever adapted to serve as means for lifting the door toward closed position. 45 110
28. In a railway car having a lading discharge opening, a hingedly mounted closure for said opening having a marginal flange adjacent its free edge terminating in an angularly disposed portion, an arm carried by the closure having a portion substantially normal thereto, said arm having portions projecting on opposite sides of said normal portion rigidly secured to the angularly disposed portion of the marginal flange of the closure, and means movably mounted upon the car body and cooperable with the arm for supporting the closure in operative position. 50 115
29. In a railway car having a lading discharge opening, a hingedly mounted closure for said opening having a marginal flange adjacent its free edge, said closure being integrally provided with a reinforcing member disposed inwardly and extending substantially parallel with said marginal flange, said member and flange being cooperable with a removable lever adapted to extend beyond the free edge of the door to serve as means whereby the door may be lifted toward closed position. 55 120
30. In a railway car having a lading discharge opening, a hingedly mounted closure for the opening having a marginal flange adjacent its free edge, said closure being integrally provided with a plurality of reinforcing members extending substantially normal to said flange and with a member disposed inwardly of and extending substantially parallel with said flange for connecting said reinforcing members, said connecting member and flange being cooperable with a removable lever adapted to extend beyond the free edge of the door to serve as means whereby the door may be lifted toward closed position. 60 125
31. In a railway car having a lading discharge opening, a hingedly mounted door for closing the opening, said door being provided adjacent its free edge with a marginal flange and with a rigidifying flange extending inwardly from the latter, said marginal flange terminating in an outwardly projecting portion substantially parallel to the main body of the door, an arm having angularly disposed portions respectively secured to said rigidifying flange and to said portion of the marginal flange, and means engageable with said arm for maintaining the door in closed position. 65 130
32. In a railway car having a lading discharge opening, a hingedly mounted door for closing the opening having a plate-like body portion, the free edge of said door being provided with a marginal flange terminating in an angularly disposed portion substantially parallel with said plate-like body portion, a rigidifying member rigid with the door and extending inwardly from adjacent the free edge thereof, an arm having a plurality of flanges, ones of said flanges being rigidly secured to said plate-like body portion and to said angularly disposed portion and the other of said flanges being rigidly secured to said rigidifying member, and means engageable with said arm for maintaining the door in closed position. 70 135
33. In a railway car having a lading discharge opening, a hingedly mounted closure for said opening, said closure having a marginal flange adjacent its free edge terminating in an angularly disposed portion, an arm mounted on the closure and projecting beyond the free edge there- 75 140
- 75 145
- 75 150

of, said arm being provided with a flange secured to said angularly disposed portion and being also provided intermediate its ends with a laterally projecting bracket secured to said portion, and a member movably mounted on the car body engageable with said flange of the arm for supporting the closure in operative position.

34. In a railway car having a lading discharge opening, a hingedly mounted door for closing said opening, the free edge of the door being pro-

vided with a marginal flange terminating in an angularly disposed portion, an arm of substantially channel shape cross section mounted on the door, said arm being provided with a laterally projecting bracket rigidly secured to said angularly disposed portion of the door, and a member movably mounted on the car body having a portion engageable with said arm for supporting the door in closed position.
